POWER OUTLET BOX

Merle A. Plummer, North Hollywood, Calif., assignor to
Myers Electric Products, Inc., Montebello, Calif.

Filed Aug. 4, 1972, Ser. No. 286,108

Term of patent 14 years

Int. Cl. D13—03

U.S. Cl. D26—1 B

FIG. 1 is a perspective view of a power outlet box with the front lid closed, showing my new design.

FIG. 2 is a front elevational view thereof with the front lid raised.

FIG. 3 is a bottom plan view of FIG. 1.

FIG. 4 is a top plan view of FIG. 1.

FIG. 5 is a rear elevational view of FIG. 1.

FIG. 6 is a side elevational view as seen from the left of FIG. 1.

FIG. 7 is a side elevational view as seen from the right of FIG. 1.

I claim:

The ornamental design for a power outlet box, substantially as shown.
